(57) **CLAIM**

I claim the ornamental design for a serving tray with cutting board inserts, as shown and described.

DESCRIPTION

FIG. 1 is an exploded view of the serving tray with cutting board inserts.

FIG. 2 is a perspective view of the serving tray with cutting board inserts shown in FIG. 1.

FIG. 3 is a front elevational view of the serving tray with cutting board inserts, the rear elevational view being identical.

FIG. 4 is a right side elevational view of the serving tray with cutting board inserts; and,

FIG. 5 is a left side elevational view of the serving tray with cutting board inserts.

Broken lines illustrate features or environmental components that are not part of the design sought to be patented.
